UNITED STATES PATENT OFFICE.

JESSE C. KING, OF LA JUNTA, COLORADO, ASSIGNOR OF ONE-HALF TO AARON WILKINS, OF LA JUNTA, COLORADO.

CENTRIFUGAL FILTERING OR DEWATERING MACHINE FOR ORE-PULP.

1,088,823.

Specification of Letters Patent.

Patented Mar. 3, 1914.

Application filed July 19, 1913. Serial No. 780,045.

To all whom it may concern:

Be it known that I, JESSE C. KING, a citizen of the United States, residing at La Junta, in the county of Otero and State of Colorado, have invented certain new and useful Improvements in Centrifugal Filtering or Dewatering Machines for Ore-Pulp, of which the following is a specification, reference being had to the accompanying drawings.

This invention relates to ore filters or slimers and more particularly to a centrifugal filtering or dewatering machine for ore solutions for separating the slime pulp therefrom of the metal bearing solution, the primary object of the invention residing in the provision of improved means for discharging the slime pulp from the machine.

The invention has for another object to provide a plurality of filters arranged at the outer edge of a rotary platform or bed plate upon which the ore impregnated solution is received, and means for elevating the filters at intervals during the rotation of the solution supporting platform and turning said filters whereby the slime which has collected thereon is discharged by centrifugal action.

A further object of the invention resides in the provision of improved means for mounting a series of filters for pivotal and vertical movement, a plate carried by each of the filters to replace the same at the outer edge of the rotating platform, when the filters are elevated, means for elevating the filters, and additional means to turn the filters as they are moved upwardly, whereby the slime which has collected upon the screening surface of the filters is thrown outwardly therefrom into a suitable receiving tank.

The invention has for still another object the provision of an improved filter construction having opposed filtering screens adapted to be alternately disposed for engagement by the ore carrying solution.

Another object of the invention is to produce a machine for the above purpose which is comparatively simple in its construction, highly efficient and durable in practical operation, and will effect a thorough separation of the slime pulp from the remainder of the solution.

With the above and other objects in view, the invention consists in certain construc-

tions, combinations, and arrangements of parts that I shall hereinafter more fully describe and claim.

For a full understanding of the invention, reference is to be had to the following description and accompanying drawings, in which—

Figure 1 is a vertical section of a machine embodying the present invention. Fig. 2 is a horizontal section taken on the line 2—2 of Fig. 1. Fig. 3 is a fragmentary vertical section, showing one of the filters disposed in its discharging position. Fig. 4 is an enlarged fragmentary view illustrating the mounting of the filters. Fig. 5 is an enlarged section taken on the line 5—5 of Fig. 4. Fig. 6 is an elevation of one of the filters removed. Fig. 7 is a section taken on the line 7—7 of Fig. 4. Fig. 8 is a detail elevation of the filter turning pinion.

Referring in detail to the drawings, 5 designates the corner posts or uprights of a hexagonal frame structure, said uprights being preferably formed of angle iron. A series of horizontal metal beams 6 connect these angular uprights, and additional lower I-beams 7 are arranged in parallel relation and fixed at their ends to the lowermost connecting beams 6 by means of suitable bracket plates 8. The I-beams 7 are disposed upon opposite sides of the vertical center of the frame structure, and are connected at intervals by the transverse brace bars 9.

A bearing block 10 is provided in its upper surface with annular raceways 11 to receive the bearing balls 12. The block 10 is provided with a central opening to receive the reduced lower end 14 of a vertical shaft 13. A cap plate 15 is fixed upon the lower end of said shaft, and rests upon the annular series of bearing balls 12. A head block 16 is keyed or otherwise secured to the upper end of the shaft 13 and is provided with an internally threaded socket to receive the inlet pipe 17. This pipe in its lower end is provided with annular series of elongated slots 18, and has its upper end disposed in a supporting collar 19, suitably fixed between and to a pair of horizontal parallel T-bars 20, which constitute a part of the supporting frame.

A plurality of radially disposed T bars 21 are suitably secured at their inner ends to the head block 16. These bars are slightly

inclined upwardly from their inner to their outer ends, and upon the same the bed plate or platform 22 is secured. This bed plate serves as a receiving table for the ore carrying solution. A series of metal castings, generally indicated by the numeral 23, are bolted together at their abutting vertical edges, said castings being mounted upon and depending below the outer ends of the 10 T bars 21. Each of these castings includes an upwardly extending channeled bar 24. It will be understood from reference to Fig. 4 of the drawings, that the channels of the bars 24 are continued in the body of the 15 castings 23, so that said channels in adjacent castings provide guide-ways for the filters 25. Any desired number of these filters may be employed in accordance with the capacity of the machine. Each of the 20 castings is provided with comparatively wide and narrow vertical channels 26 and 27, respectively.

28 designates a slide bar which is vertically movable in the wider channel 26 and 25 a block 29 is arranged within the inner face of this channel. A pair of these blocks arranged in the channels 26 of the opposed guide castings constitute the ends or heads of the filters 25. In the smaller channels 27 30 the elevating bars 30 are disposed, the upper ends of said bars being engaged upon the trunnions 31 which are fixed in the head blocks 29.

Each of the filters is of duplex construction and includes the filtering cloths 32. Each filtering cloth is arranged between a pair of curved wire mesh screens 33, the edges of the cloth in the screen being secured together by suitable binding strips. 40 The curvature of each of the two filtering cloths 32 and the pairs of wire screens 33 is such as to dispose the same, when arranged contiguous to the periphery of the outer or bed plate 22, in concentric relation thereto. The two filtering screens are 45 spaced from each other, as clearly shown in Fig. 5, and held in such spaced relation by means of the head blocks 29 and an intermedie block 34, suitable bolts or rivets 50 55 securing the spaced screens to said blocks.

As before stated, each of the head blocks 29 of the filter is provided with a trunnion 31. These trunnions which are arranged in 55 the upper ends of the elevating bars 30 are mounted for vertical movement in the slots 36 provided in the uprights 24 formed on the castings 23. One trunnion of each filter has a suitable head fixed thereto to retain the same in the slot of one of the casting uprights 24, while upon the other trunnion of the filter disposed in the slot of the opposed upright, a pinion 38 is mounted. This pinion is loose upon the filter 60 trunnion and carries a pawl 39 for engage-

ment with the teeth of a ratchet 40 which is fixed upon the trunnion 31. To the upright 24 or casting which is disposed contiguous to the pinion 38, a rack 41 is secured. The pinion is adapted for engagement with the teeth of this rack in the upward movement of the filter so as to turn said filter, for a purpose which will be more fully pointed out in the description of the operation of my machine, which will presently follow. The upper ends of the uprights or vertical extensions 24 of the castings 23 are connected by the bars 42 so as to brace and strengthen the same, and radially disposed truss rods connect said bars to a collar 44 which is fixed upon the inlet pipe 17 immediately beneath the bearing block 19.

45 indicates a transversely curved annular plate which is suitably secured to the inner face of the guide uprights 24 and is disposed above and in spaced relation to the table or bed plate 22. This transversely curved plate acts as a guard and prevents the solution being thrown outwardly over the upper edges 50 of the filters by centrifugal force during the rotation of the table. As shown in Fig. 1, the filters are of sufficient height to extend between the table and this inwardly extending curved guard plate. The several filters 55 may be angularly adjusted so as to facilitate the collection and discharge of the slime pulp therefrom by means of the screws 46 which are threaded in the movable bars 28 and are adapted for binding engagement 100 with the head blocks 29 of the filter.

To the lower ends of the elevating bars 30, an angle bar 47 is secured, said angle bar being of substantially U-shape form, as clearly shown in Fig. 4. To the parallel 105 portions of this angle bar, a plate 48 is securely riveted, the upper edge of said plate engaging the lower end of the filter 25. This plate is adapted to take the place of the filter when said filter is rotated or elevated 110 to discharge the slime pulp in the manner to be later explained. The several bars 47 are connected by means of radially disposed T bars 49 to a sleeve 50 which is keyed, as at 51 upon the vertical shaft 13. Obliquely disposed brace rods 52 connect the lower end of said sleeve to the radial bars 49. The sleeve 50 at its lower end is mounted to rotate in a bearing casting 53 which is bolted or otherwise secured to the channel bars 54. The 120 ends of these channel bars are engaged against the outer faces of the inwardly extending flanges of the vertical parallel angle bars 55 which are bolted or otherwise secured at their upper and lower ends to the connecting bars 6 between the several uprights 5 of the frame structure. The channel bars 54 are connected adjacent their ends by the transverse plates 56, each of said plates being provided with a central cylindrical en- 125 130

largement having a vertical threaded bore to receive an adjusting screw 57. As each of the means for operating the adjusting screws is identical, it is understood that the following description of one such operating means applies with equal force to both.

Upon the lower unthreaded portion of each screw 57, a pair of connected miter gears 58 are keyed for sliding movement, the beveled teeth of said gears being disposed in relatively opposite directions. One of these gears has a collar 59 formed therewith to receive a yoke 60 on one end of an operating lever 61.

62 indicates the power transmission shaft mounted in suitable bearings 63 bolted or otherwise secured upon the connecting bars 7 between the beams 6. One end of this shaft is provided with a beveled pinion 64 disposed between the opposed gears 58 and to the other end of said shaft a beveled gear 65 is fixed and meshes with a similar gear 66 which is loosely mounted upon the shaft 13. This latter gear is arranged between a collar 67 fixed upon the shaft and a sliding clutch member 68 keyed on said shaft. This clutch member is adapted to be actuated by means of a lever 69 and is yieldingly held in engagement with the clutch face of the gears 66 by means of a heavy coil spring 70 arranged upon the shaft 13 and bearing at one end against the clutch member and at its other end against the collar 71 fixed to said shaft.

73 designates the power shaft mounted in suitable bearings in the frame of the machine and having a drive pulley 74 secured to one of its ends whereby the same may be driven by means of a belt extending to an engine or other suitable source of power. To the opposite end of this shaft 73, a beveled gear 75 is fixed and meshes with a similar gear 76 fixed upon the lower end of the vertical shaft 13.

45 A gear shifting rod 77 is mounted for vertical movement in a suitable guide 78 fixed upon the upper end of the lifting screw 57. A sleeve 79 secured to the plate 56 is loosely engaged upon this rod and is adapted to 50 contact with stop collars 80 which are adjustably mounted upon the rod 77 by means of suitable set screws. The lower end of the rod 77 is connected to the yoke of the elevating lever 61. The levers 61 for actuating 55 the movable bars or gears 58 are fulcrumed, as indicated at 81 upon one of the lower horizontal I beams 7, and are convergently disposed and connected to a common actuating lever 82, whereby the pairs of gears may 60 be simultaneously shifted.

A tank 83 is disposed within the frame uprights 5 and is suitably secured thereto. This tank is provided with spaced annular inclined walls 84, whereby the same is divided into upper and lower compartments

85 and 86 respectively. The lower compartment 86 of the tank is provided with two outlets for the purpose which will be later referred to, while the upper compartment 85 has a single outlet. This latter compartment receives the slime pulp, while the solution in which the ore is carried and the water are received in the lower compartment.

70 75 80 85 90 95 100 105 110 115 120 125 130

87 indicates a pipe extending from the tank or reservoir containing the solution and having its discharge end disposed over the upper open end of the inlet pipe 17. A suitable supply controlling valve 88 is arranged in this pipe. A water supply pipe 89 is connected to the pipe 87 and in the same a control valve 90 is arranged.

Having now described the particular construction of my machine, the operation of the same will be understood as follows: The primary purpose of the machine is to filter 85 the slime pulp from a cyanid solution, although it will be understood that the machine is also well adapted to the de-watering or sliming of ore solutions containing precious metals. The ore impregnated solution is fed through the medium of the inlet pipe 17 to the table or bed plate 22. The machine is set in operation by releasing the clutch member 60 whereby the gear 66 is locked upon the shaft 13 and motion is then 95 transmitted to said shaft from the power shaft 73. As the shaft is rotated, the parts fixed thereon, namely, the supporting table and the filter supporting beams 49 will also be rotated. The centrifugal force thus generated, throws the solution outwardly through the slots 18 in the lower end of the inlet pipe and against the innermost screens of the filter. The slime banks up against these filter screens, the solution passing through the screens and into the lowermost compartment 86 of the tank 83, from which the same is thrown off through one of the outlets of said compartment and conveyed back to the solution tank by means of a suitable pipe or conduit. When the operator is 100 of the opinion that a sufficient amount of slime pulp has collected on the filtering screens, the feed of the solution to the rotating table is cut off and the pairs of the miter gears 58 are shifted in the proper direction to engage one of said gears with the power transmission pinions 64 of the shaft 62. The vertical adjusting screws 57 are thus rotated, and as said screws are threaded in the plates connecting the channel bars 54, said bars, together with the beams 49 of the filters, and replace plates 48 mounted thereon will be elevated, the filter trunnions moving upwardly in the slots 36 of the guide up- 105 rights 24. In this upward movement of the filters, the pinions 38 thereof are brought into engagement with the teeth of the racks 41, and as said pinions are locked to the ratchets of the filter trunnions, the several 110 115 120 125 130

filters are turned and horizontally disposed above the inwardly curved guard plate 45, as indicated in dotted lines in Fig. 4. It is, of course understood that as the sleeve 50 is keyed upon the shaft 13, the filters are constantly rotated through their upward movement. Thus, when said filters are reversed or turned over, as will be later clearly understood, the centrifugal force acts to throw the slime pulp outwardly from the screening surfaces and into the upper chamber or compartment 85 of the collecting tank. As the several filters move upwardly, their place is taken by the plates 48 so that the escape of the solution from the rotating table or bed plate 22 is prevented. After the slime pulp has thus been discharged into the upper compartment of the tank, the operator reverses the movement of the connecting gears 58 and 20 engages the other of said gears with the pinion 64, thus reversing the rotation of the screws 57 and lowering the filters. It is to be noted that the sleeve 79 engaging the upper stop collar 80 on the rod 77, moves 25 said rod to shift the gears 58 automatically, discontinuing the upward movement of the filters. In the reverse or downward movement of the filters, the pinions 38 rotate loosely upon the filter trunnions in their 30 movement upon the racks 41, and as the filters are lowered, the positions of the screening surfaces are reversed from that which they formerly occupied so that after each discharge of material, the screen which 35 was previously disposed outwardly is arranged inwardly in opposed relation to the solution. If any slime pulp remains upon the screening surface, after the screens have been lowered to their normal positions, 40 water may be supplied to the inlet pipe 17 by turning the valve 90 in the water supply pipe 89. This water passing through the screens of the filters, removes such slime pulp as may adhere to the outer screen and 45 carries the same into the lowermost compartment 86 of the tank, from which the same may be drawn off through the other of the outlets, and said ore particles collected in any desired manner.

50 From the foregoing, it will be seen that I have provided a filtering or de-watering machine for the collection of slime pulp, which will be highly efficient and reliable in its operation and will separate the slime pulp 55 from the ore solution, after which the precious metals may be readily removed from the cyanid solution by any suitable process, as will be readily understood. It will further be appreciated that as the machine is 60 comparatively simple in its construction, the same can be produced at small manufacturing cost.

While I have shown and described the preferred construction and arrangements of the 65 several elements, which is susceptible of con-

siderable modification therein, I reserve the right to resort to all such legitimate changes as may be fairly embodied within the spirit and scope of the appended claims.

Having thus described my invention, what I claim, is:

1. In a centrifugal machine, a plurality of screens mounted for rotation about a common axis, means for moving the screens bodily in a plane parallel with said axis, and 75 additional means for disposing the several screens in planes at right angles to their axes of rotation.

2. In a centrifugal machine, a rotary table, a plurality of filtering screens mounted upon the outer edge of said table and normally stationary with respect thereto, said screens being disposed in parallel relation to the axis of the table, means for elevating the screens above the bed of material 80 upon the table, and additional means for automatically turning the screens as they are elevated and disposing the same in planes 85 at right angles to the rotary axis of the table.

3. In a centrifugal machine, a plurality of filtering screens mounted to rotate about a common axis, means for rotating said screens, means rotatable with the screens to feed the ore impregnated solution to said 95 screens, means for moving the screens in a plane parallel to their axis of rotation, and additional means for angularly disposing the screens with relation to their axis of rotation whereby the slime collected thereon is 100 discharged by centrifugal force.

4. In a centrifugal machine, a plurality of filtering screens mounted to rotate about a common axis, means for rotating said screens, means rotatable with the screens to feed the ore impregnated solution to said screens, means for moving the screens in a plane parallel to their axis of rotation, and means for bodily turning the said screens about individual axes, whereby the slime collected 105 thereon is discharged by centrifugal force.

5. In a centrifugal machine, a plurality of filtering screens mounted to rotate about a common axis, means for rotating said screens, means for feeding the ore impregnated solution to the screens, means for moving said screens in parallel relation to their axis of rotation, and individual means for moving each screen during said latter movement to an angular position with relation to its rotative axis whereby the slime collected 115 thereon is discharged by centrifugal force.

6. In a centrifugal machine, a rotary table, a plurality of vertically movable filtering screens arranged at the outer edge of said table, and rotatable with the same, means for feeding the ore impregnated solution to the screens, a replaceable plate movable with each screen, and means for ele- 120 125 130

vating the screens and plates to dispose the screens above the solution for the removal of the slime pulp therefrom and positioning the replacer plates at the outer edge of the table 5 to retain the solution thereon.

7. In a centrifugal machine, a rotary table, a plurality of vertically movable filtering screens arranged at the outer edge of the table to rotate therewith, said screens 10 being mounted to rotate about individual axes, a replacer plate movable with each of the screens, means for feeding the ore impregnated solution to the screens, and means for elevating the screens above the solution 15 and rotating the same in their upward movement to angularly dispose the screens with relation to their axis of rotation, whereby the slime pulp is discharged therefrom by centrifugal force, said replacer plates occupying 20 the normal positions of the screens at the outer edge of the table to retain the solution thereon.

8. In a centrifugal machine, a rotary table, a plurality of vertically movable filtering screens arranged at the outer edge of said table to rotate therewith, said screens being also mounted to rotate about individual axes, means for feeding the ore impregnated solution to the screens, a pinion 25 mounted upon the axis of each screen, racks to be engaged by said pinions, and means for elevating the screens upon the table and engaging the pinions with said racks to turn said screens and angularly dispose the 30 same with relation to their axis of rotation, whereby the slime collected thereon is discharged therefrom by centrifugal force.

9. In a centrifugal machine, a rotary table, a plurality of filtering screens mounted at the outer edge of said table to rotate therewith, each of said screens having spaced screening surfaces, said screens being also mounted to rotate about individual axes, means for effecting said individual rotation 45 of the screens to angularly dispose the same with relation to their common axis of rotation, whereby the slime is discharged from the screens by centrifugal force, said rotation of the screens alternately presenting the 50 screening surfaces to the solution when the screens return to their normal position.

10. In a centrifugal machine, a rotary table, a plurality of filtering screens mounted at the outer edge of said table for vertical movement and also for rotation about individual axes, a replacer plate vertically movable with each of the screens, means for moving said screens and plates to elevate the screens above the ore solution and to dispose said plates in the positions normally occupied by the screens whereby the solution is retained in the table, and means for individually rotating said screens during their upward movement to position the same at an angle with relation to their common axis of rotation, whereby the slime collected upon the screens is discharged therefrom by centrifugal force. 55

11. In a centrifugal machine, a rotary table, a plurality of filtering screens mounted upon the outer edge of said table for bodily vertical movement, and means for elevating the several screens above the bed of material upon the table. 70

12. In a centrifugal machine, a rotary table, a plurality of filtering screens mounted upon the outer edge of said table for bodily vertical movement, each of said screens having a rotative axis, means for elevating the screens above the bed of material upon the table, and additional means for rotating the several screens upon their axes to dispose the same at an angle from their normal positions with relation to the rotary axis of the table. 80

13. In a centrifugal machine, a rotary table, spaced vertical guides arranged at the outer edge of said table, a filtering screen mounted in each of said guides for vertical movement, means for simultaneously elevating the several screens above the bed of material on the table, and additional means movable in said guides to occupy the normal positions of the screens when the latter are elevated and retain the material upon the table. 85

In testimony whereof I hereunto affix my signature in the presence of two witnesses.

JESSE C. KING.
